UNITED STATES PATENT OFFICE.

CARL W. BRUCE, OF TORONTO, ONTARIO, CANADA.

SCREENING APPARATUS.

1,405,269.

Specification of Letters Patent. Patented Jan. 31, 1922.

Application filed July 1, 1921. Serial No. 481,842.

To all whom it may concern:

Be it known that I, CARL W. BRUCE, a subject of the King of Great Britain, and resident of 22 Maitland St., in the city of

5 Toronto, in the county of York, in the Province of Ontario, in the Dominion of Canada, have invented certain new and useful Improvements in Screening Apparatus, of which the following is a specification.

10 The invention relates to improvements in screening apparatus as described in the present specification and shown in the accompanying drawings that form a part of the same.

15 The invention consists essentially of the novel means employed for imparting a vibratory motion to a screen.

The objects of the invention are to insure proper screening of the material, to 20 lessen the cost of such work and generally to provide screening apparatus which will be inexpensive of construction, efficient in operation, and durable.

In the drawings Figure 1 is a diagrammatic view of a screen and the means adapted for vibrating same.

Figure 2 is a side elevation of a modified form of mechanism for vibrating the screen.

Figure 3 is a plan view of a portion of 30 a screen and showing one of the guides therefor.

Like numerals of reference indicate corresponding parts in the various figures.

Referring to the drawings 1 is an elongated 35 tapered chute swingingly supported at its forward end in a frame 2 by means of arms 3 pivotally secured to the opposing inner faces of said frame and pivotally secured to the outer sides respectively of said chute, 40 said chute being supported to the rear of its longitudinal centre by means of a yoke 4 pivoted to opposite sides thereof and having a connecting arm 5 pivotally depending from a link 6 which in turn is pivotally supported centrally thereof from a beam 6^a or other desirable supporting member.

The rear portion of the chute is provided with a screen bottom forming a sieve 7 through which the fine particles of sand or 50 other material being screened are adapted to pass into any convenient form of receptacle adapted to be located therebelow.

8 is a bar pivotally secured to the free end of the link 6 and extending substantially 55 at right angles to the arm 5 and supporting from its free end a split collar 9.

10 is a line shaft rotatably mounted in a bearing member 11 supported by the beam 6^a and having rigidly mounted thereon an eccentric member 13 operating within the collar 9 and adapted on rotation to impart a reciprocating movement to the bar 8 and as said bar 8 and the arm 5 are pivoted to opposite ends of the pivoted link 6 a vertical reciprocating movement will be imparted to said arm and consequently to the rear portion of the chute. 14 are rollers rotatably mounted on pins 15 projecting outwardly from opposite sides of the chute 1 slightly to the rear of the yoke 4 and being adapted to reciprocate vertically in guides in the frame 2, said guides each comprising two members 16 of right angular cross section secured to the inner sides of the frame at a slight rearward angle, so that 70 the vertical reciprocatory movement imparted to the chute will be translated to a swinging motion thus serving to thoroughly agitate the material on the screen and impart a slight forward impetus to the large 80 particles to start them on their way down the chute.

In Figure 2 of the drawings a modified form of construction is shown in which the arm 5 from the chute is provided at its upper 85 end with a split collar 17 in which operates an eccentric member 18 which is rigidly mounted on a horizontal shaft 19 journaled in brackets 20 from a beam 21, said shaft 19 being connected to a driven pulley 22 by 90 means of a belt 23 operating over said driven pulley and over a pulley 24 on said shaft 19.

In the operation of this invention the shaft 10 is set in motion through the operation of the drive mechanism and the sand or other material is fed to the screen 7 by any convenient means and as the chute is pivotally supported by the yoke 4 and the arms 3 a swinging motion is imparted there- 100 to through the vertical movement of the arm 5 and the rollers 14 operating between the rearwardly inclined guide members 16, causing the small particles to be forced through the screen into a convenient form 105 of container while the larger particles roll down the chute.

What I claim is:—

In screening apparatus, a frame, a chute swingingly mounted at its forward end in 110 said frame, and having the rear portion of its bottom in sieve form, a yoke pivotally

secured to said chute adjacent to said sieve portion and having an upwardly projecting rigid arm, a supporting bracket, a link pivoted centrally thereof to said supporting member and at one end being pivotally connected to said arm, a horizontally arranged bar pivoted to the other end of said link and carrying at its outer end a split collar, a line shaft, an eccentric rigid with said shaft and operating in said split collar for reciprocating said bar, rearwardly extend-

ing guide members secured to the inner faces respectively of said frame and rollers projecting from the outer sides of said chute and operating between said guide members. ¹⁵

Signed at the city of Toronto, this 24th day of June 1920.

CARL W. BRUCE.
